Des. 203,152

Patented Dec. 14, 1965

203,152

SAFETY HELMET

John L. Marchello, Ann Arbor, Mich., assignor to Joseph Buegeleisen Company, Southfield, Mich., a corporation of Michigan

Filed Oct. 23, 1964, Ser. No. 82,295

Term of patent 14 years

(Cl. D3—13)

FIG. 1

FIG. 2

FIG. 3

FIG. 4

FIG. 1 is a top plan view of a safety helmet showing my new design;

FIG. 2 is a side elevational view thereof, with the opposite side being identical in appearance.

FIG. 3 is a front end view thereof.

FIG. 4 is a rear end view thereof.

I claim:

The ornamental design for a safety helmet, as shown and described.
